US00D908657S

(12) **United States Design Patent** (10) **Patent No.:** **US D908,657 S**
(45) **Date of Patent:** **** Jan. 26, 2021**

(54) **SERVO AMPLIFIER**

(71) Applicant: **Mitsubishi Electric Corporation**,
Tokyo (JP)

(72) Inventors: **Shinichi Kato**, Tokyo (JP); **Asuna Osawa**, Tokyo (JP); **Masaaki Kadoyanagi**, Tokyo (JP); **Shotaro Hirako**, Tokyo (JP)

(73) Assignee: **Mitsubishi Electric Corporation**,
Tokyo (JP)

(**) Term: **15 Years**

(21) Appl. No.: **29/632,968**

(22) Filed: **Jan. 11, 2018**

(30) **Foreign Application Priority Data**

Jul. 25, 2017 (JP) 2017-016007

CLAIM

The ornamental design for a servo amplifier, as shown and described.

DESCRIPTION

FIG. 1 is a front, top, and right side perspective view of a servo amplifier showing our new design;
FIG. 2 is a rear, bottom, and left side perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines illustrate portions of the servo amplifier that form no part of the claimed design.

1 Claim, 8 Drawing Sheets
